OSCAR B. BLAKE AND ORMOND E. COLONY, OF KEENE, NEW HAMPSHIRE.

Letters Patent No. 80,852, dated August 11, 1868.

MEASURING-FAUCET.

The Schedule referred to in these Letters Patent and making part of the same.

TO ALL WHOM IT MAY CONCERN:

Be it known that we, OSCAR B. BLAKE and ORMOND E. COLONY, of Keene, in the county of Cheshire, and State of New Hampshire, have invented a new and useful improved Faucet for Measuring Liquids; and we do hereby declare that the following is a full, clear, and exact description thereof, reference being made to the accompanying drawings, making a part of this specification.

This is designed more particularly for drawing oils into small cans or oilers, such as are commonly used for lubricating machinery, and being made of proper size to allow only a sufficient quantity to pass, at each draught, to fill a can, it will prevent much of the waste occasioned by usual methods; but by making the receiving or measuring-chamber of proper capacity, it may be used for other purposes.

It consists essentially of a measuring-chamber or receptacle, of sufficient capacity to contain the requisite amount of liquid, with a faucet, having an arrangement of chambers and orifices, which may alternately be brought into positions to form passages for the flow of the liquid from a can or reservoir into the measuring-chamber, or from the measuring-chamber through an outlet into the vessel which it is designed to fill, the same being provided with suitable passages to admit air to supply the place of the liquid as it is drawn out, all of which are so arranged that but one set of passages can be open at the same time, so that it cannot be left in a position to allow the flow or waste of the liquid from the supply-fountain.

To enable others skilled in the arts to make and use our invention, we will proceed more fully to describe its construction and operation.

Figure 1 is a perspective view of same, as attached to a tank or can.

Figures 2 and 3 are sectional views through the centre of the faucet, showing the faucet in its different positions for forming the induction and eduction-passages.

Similar letters of reference are used to indicate like parts in each of the drawings.

A is a tube or pipe, which, being connected with a reservoir or supply-fountain, forms a part of the induction-passage to the measuring-chamber or receptacle B. The upper wall of this passage is made inclined, rising toward the reservoir, which facilitates the escape of air from the measuring-receptacle B, which is also constructed with its upper and lower walls converging from the faucet, so as to promote the egress of air and liquids from it in either direction.

The faucet consists of a cylindrical casing, C, and conical plug, C', which may be turned about one-half a revolution therein, being stopped by the pin L striking against a projection on the lower end of the casing, when it is turned in either direction to proper positions to open the induction or eduction-passages of chamber B.

The plug C' is made with a chamber or cavity, H, which is open from one side, and, when turned, as shown in fig. 2, its openings correspond with the orifices D and E in the casing, thus opening the induction-passage to the receptacle B, so that it may be filled from the supply-fountain. I is another chamber, separated from H by the partition K. This has an opening on the surface of the plug, on the opposite side from that of chamber H, and, when turned, as shown in fig. 3, it coincides with the orifice F, making an eduction-passage from receptacle B, to discharge its contents through the outlet O at the lower end of the faucet. When in this position, the chamber H comes in contact with the hole M, and air is admitted through that and the passage N into receptacle B, so that its contents will be more readily discharged, and when the faucet is turned again to open the induction-passage, the air contained in B will ascend into the can or reservoir, and supply the place of the liquid drawn out. This precludes the necessity of having any other vent, and is an item of no small importance when it is used for liquids of a volatile nature, which lose much by evaporation when not kept in close-vessels.

The receptacle B may be made of a capacity to hold any amount which it is desired to measure at one time, and it may be made of any form or shape adapted to the purpose or position in which it is to be used, and the induction-pipe A may be provided with any suitable means to attach it to a tank, can, barrel, or other vessel, without any material change of the essential features of the invention.

We claim as our invention, and desire to secure by Letters Patent—

The inclined tube or induction-pipe A, and converging measuring-receptacle B, in connection with the faucet, having an outer casing, C, with orifices D, E, and F, and a semi-rotating plug, C', having chambers H and I, and stop-pin L, arranged so as to form alternately the induction and eduction-passages for the supply and discharge of the liquids to and from the measuring-receptacle B, the same being provided with passages M and N, or their equivalents, for the admission of air to supply the place of the liquids as they are drawn from the can or reservoir; the whole being constructed and arranged substantially as herein shown and described.

OSCAR B. BLAKE,
ORMOND E. COLONY.
